TAP BUSH

Frank E. Rice, Detroit, Mich., assignor to American Tap Bush Company, Detroit, Mich., a corporation of Michigan

Application August 16, 1933, Serial No. 685,324

4 Claims. (Cl. 217—113)

The present invention relates to tap bush and method of making the same.

Recently, metal barrels and kegs have been employed by manufacturers of liquors for packaging the liquors. The use of metal barrels for such purposes has created a demand for tap bushes which may be welded or screwed in place in the barrels and which must be made at minimum cost to the barrel manufacturers, and which, at the same time, must be capable of receiving the taps in use at the present time.

The present invention, therefore, is addressed to such tap bushes and is concerned with tap bushes which are made in two separate parts, and subsequently fastened together in permanent relation.

The body member of the bush of the present invention, which is the part of the bush secured to the barrel, is fashioned from a blank by tool action, that is to say, the body may be formed by stamping, spinning, or drop or press forging. The neck member may be forged, stamped or cast.

In order that a tap may be applied to a bush of the present invention, in the usual manner, the body and neck members of the bush must be prevented from relative rotation during the application of the tap.

An object of the present invention is to provide tap bushes which are readily applicable to metal barrels.

Another object of the invention is to provide a method of making tap bushes by tool action.

A further object of the invention is to provide a method of making tap bushes whereby efficient and satisfactory bushes may be made at minimum cost and which bushes are easily secured in place in metal barrels.

A still further object of the invention is to provide forged tap bushes for metal barrels.

Generally speaking, the tap bush of the present invention is made in two parts, one the body part or member and the other the neck part or member. The body member is formed by tool action, such as spinning, stamping or forging, while the neck may be forged or cast. The two members are then assembled together in permanent association in such manner as to prevent relative rotation between these members.

The method of the present invention contemplates manufacturing bushings in two parts and assembling these parts together in permanent relationship.

The above, other and further objects of the invention will be apparent from the following de-

scription, accompanying drawings, and appended claims.

The accompanying drawings illustrate embodiments of the present invention, and the views thereof are as follows:

Figure 1 is a top plan view of a tap bush made in accordance with the principles of the present invention.

Figure 2 is a vertical sectional view taken through the center of the bush illustrated in Figure 1, and showing the two members in assembled relationship prior to permanent connection.

Figure 3 is a vertical sectional view taken substantially in the plane of line III—III of Figure 1, and showing the completed bush, that is with the body and neck members permanently connected together.

Figure 4 is an enlarged horizontal sectional view taken substantially in the plane of line IV—IV of Figure 3, and showing certain details of construction.

Figure 5 is a plan view of a bush, made in accordance with the principles of the present invention, illustrating another form of preventing relative rotation between the body and neck members.

Figure 6 is a vertical sectional view taken substantially in the plane of line VI—VI of Figure 5.

Figure 7 is a side elevational view of a neck member, made in accordance with the principles of the present invention, for assembly with a body to provide the completed tap bush of the present invention.

Figure 8 is a view, partially in elevation and partially in section, showing a tap applied to a tap bush, which latter is made in accordance with the principles of the present invention, and showing such bush secured in place in a double walled metal barrel.

Figure 9 is a central vertical section through a tap bush, made in accordance with the principles of the present invention, and illustrating one form of neck slightly different from that illustrated in Figure 7.

Figure 10 is a vertical central sectional view through a tap bush, such as shown in Figure 9, and taken at 90° to Figure 9.

Figure 11 is a plan view of a tap bush made in accordance with the principles of the present invention, and showing another form of the same.

Figure 12 is a vertical sectional view taken substantially in the plane of line XII—XII of Figure 11.

Figure 13 is a vertical sectional view taken sub-

stantially in the plane of line XIII—XIII of Figure 11.

The drawings will now be explained.

The tap bush of the present invention comprises a body member A and a neck member B.

The body member A is formed from a blank or piece of metal by tool action, such as by stamping, spinning or forging into the intended body form, as illustrated in Figure 2.

10 The body member A, as illustrated in Figure 2, is fashioned to provide an upper marginal attaching flange 1, a central upstanding collar 2 for receiving the pump rod, or a cork, and the collar is connected at the inner end of the bushing to a flange which defines the inner face of the bushing and connects the collar with the outer annular wall of the bushing. In the formation of the body A, the lower portion thereof is inclined, preferably, as illustrated at 3, to rigidify 15 the body member and at the same time to provide a pocket for welding material when the bush is secured in a metal barrel. The body A of Figure 2 is shown as provided with indentations 4, which are formed by being inwardly 20 struck from the exterior of the body member adjacent the collar 2, to provide lugs on the interior of the body for cooperating with the neck member B to prevent relative rotation between the neck member and the body member.

25 30 The neck member B, as illustrated in elevation in Figure 7, includes a body portion 5, a bottom outturned flange 6 which is provided with apertures 7 to receive the lugs 4 of the body member, when the parts are assembled. Along the top 35 of the neck B is provided an outstanding flange 8, the lower surface of which is inclined at 9 downwardly from the entering end 9. At the end of the inclined portion 8 the neck is formed with a stop 10, against which the lugs 11 on the tap 40 abut, when the tap is properly attached to the bush. There are two such flanges 7 with the recesses 12 therein formed by the termination of the ends 9 of the tapered part 8 and spaced from the adjacent lug 10, as illustrated in the drawings and as well understood in the art.

45 The neck B has, preferably, the upper portion of its hollow interior flared outwardly at its upper end, as illustrated at 13, to receive the upper end of the collar 2 of the body member, 50 when the same is flared by suitable tool action to permanently connect together the neck and the body.

55 After the neck B and body A have been assembled, as illustrated in Figure 2, the assembled bush is then subjected to suitable tool action to flare the end of the collar 2 so as to overlie the upper end of the neck B, as illustrated in Figure 3. This flaring of the upper end of the collar 2 60 permanently connects together the neck and the body member in assembled relationship. When the neck is applied to the body the recesses or slots 7 therein overlie the lugs 4 of the body member and thus prevent relative rotation between these members whenever a tap is secured to or 65 removed from the bush.

Figure 1 illustrates in plan a finished bush constructed in the manner described.

If desired, the flared extremity of the collar 2 may be welded to the neck B.

70 In the form of bush illustrated in Figures 5 and 6, the body member A' is made as a forging. The body member A' is submitted to suitable tool action, such as a forging machine, to provide the collar 14 for receiving the pump rod.

75 In the formation of the body member A', there

are fashioned two inwardly projecting lugs 15, which have their extremities recessed as at 16. In the formation of the neck B' the projections 17 are formed thereon which are shaped to engage the recesses 16 of the lugs 15 and thus interlock 5 the neck and body members to prevent relative rotation between these members. In this form of the invention, the neck and body are secured together in permanent relationship by flaring the upper end of the collar 14 to overlie the upper 10 end of the neck B'. This flaring is accomplished by spinning or by other suitable means, and when so flared the extremity of the collar may be welded to the neck B'.

The forged bush, just described, may be secured in position in a metal barrel by welding, or, if desired, it may be threaded to engage threads in the barrel.

Referring to the form of body member illustrated in Figures 9 and 10, it will be observed 20 that the body member A² is formed as a forging and with the collar 18 thereof provided at its outer end with an outer annular groove 19, to receive the neck B². In this form of the invention the neck B² is suitably fashioned, with the body 25 of the neck of considerably less height than the height of the interior of the bushing A², which neck is provided with the flanges 20 separated by lug receiving apertures, not shown, and provided with stops 21, adjacent these apertures or 30 slots to serve as limits for the rotation of the tap when applied to the bush. In this form of the invention the upper end of the collar 18 is flared over the neck B² when it is applied to the annular groove 19, thus securing together in 35 permanent relationship the neck and body members. If desired, the joint so made may be welded.

In the forms of the invention so far described, the necks have been secured to the bodies by 40 flaring the upper ends of the rod receiving collars of the body members.

In the form of the invention illustrated in Figures 11, 12 and 13, the necks are secured to the bottom of the body members by flaring the lower 45 extremities of the necks to engage against the outside of the bottoms of the body members.

Figure 12 illustrates a bush body A³, which may be made as a forging, and which, when formed, is provided with a central aperture 21 and inwardly thereof, the bottom of the body member is provided with an annular rabbet or groove 22. The neck member B³ may be formed as a forging, and as so formed is provided with a finished upper extremity 23 and a hollow interior 50 55 24 serving as the pump rod receiving space. The neck B³ is provided with a flange 25 which seats in the groove or undercut 22, in the bottom of the body A³. When the neck is fastened, it is provided with an extremity 26, which passes through 60 the opening 21 in the bottom of the body member A³ and is then spun or peened, as at 27, to permanently connect the neck and the body in assembled relationship.

The body A³ is, when formed, provided with 65 lugs 28 having recessed ends 29 while the neck B³ is provided with projections 30 to enter the recesses 29 of the lugs 28, for preventing relative rotation between the neck and body.

The bush illustrated in Figure 13 is made similarly to that illustrated in Figure 12, except that the body A⁴ is thinner than the body A³, and may be formed as a stamping.

The bottom of the body A⁴ is provided with a centrally disposed aperture 4. The neck B³ is 75

fashioned with the rod receiving recess or opening 32, the marginal flanges 33 for cooperating with the top, and with the upper margin finished as at 34. The neck has its lower end reduced in outer diameter to provide a portion for passing through the aperture 31 in the bottom of the body A⁴ where the extremities of the reduced portion are then spun or peened over at 35 to permanently connect together the neck and the body.

Figure 8 illustrates a bush of the present invention as employed in a bush opening in a metal barrel. Here the barrel is illustrated as a double walled barrel, 36 being the outer wall and 37 the inner wall. A bush opening is provided in these walls and the bush E applied thereto and secured by welding at the joints indicated at 38.

A tap C, of well-known construction, is removably attached to the bush by engagement of the lugs 11 of the tap collar 39 passed through the notches formed in the flanges of the neck, and the collar is then given rotative movement until the lugs 11 engage against the stops provided in the bush. The lugs 11 engage the tapered undersurfaces of the flanges to draw down the tap into tight engagement with the neck so that the sealing washer 40 is firmly clamped between the top and the bush to provide a leak-tight joint for the pump. The pump rod 41 is then inserted through the tap C and through the recess or opening provided in the bush so that the rod may withdraw the contents of the barrel in the usual manner.

The collar 40 is tightened on the tap C by a threaded sleeve 42 cooperatively engaging the tap and the collar 40, in the usual manner.

The neck of the present invention is adapted to receive taps in use at the present time, so that it will be unnecessary to secure additional taps.

The body and neck are assembled, and then a part of one is wedged or otherwise forced, by suitable action, into tight engagement with the other, to connect them together in permanent relation.

In order to provide means for preventing accidental displacement of a cork in a tap, projections or lugs 43 may be suitably fashioned on the tap bush. Other similar means may be provided such, for instance, as the indentations 44 formed in the stamped bush body A from inside the body. The inner ends of the inserted corks swell beyond the inner ends of the cork receiving portions of the bushes, and might readily be accidentally discharged by gas pressure in the barrel unless posi-

tively secured in place. The provision of the lugs 43 and indentations 44 serve as such means.

The lugs 43 and indentations 44 may be sharpened to facilitate locking engagement with a cork.

The invention has herein been described more or less precisely, but it is to be understood that the invention is not to be limited thereby, as changes may be made in the arrangement and proportion of parts, and equivalents may be substituted, without departing from the spirit and scope of the invention.

The invention is claimed as follows:

1. A tap bush having a cork receiving opening and having integrally formed means projecting from the inner face of said bush adjacent said opening and elsewhere than within said opening for preventing accidental displacement of a cork through the outer end of said opening and being so positioned as to offer no obstruction to the passage of a pump rod through the opening. 20

2. A tap bush including means defining an elongated central collar integral with an outwardly extending flange which defines the inner face of said bush, said central collar bounding a bore to receive a cork, and means on said bush and integral therewith and adjacent the inner face thereof adapted to lockingly engage a cork entered in said bore against accidental movement of the cork only in an outward direction and being so positioned as to offer no obstruction to the passage of a pump rod through the bore. 30

3. A tap bush including means defining an elongated central collar integral with an outwardly extending flange which defines the inner face of said bush, said central collar bounding a bore to receive a cork, and means on said bush and integral therewith and adjacent the inner face thereof adapted to guide the cork in its inward movement in said bore and to lockingly engage said cork against outward movement when in its normal position in the bore and being so positioned as to offer no obstruction to the passage of a pump rod through the bore. 40

4. A tap bush including flange means defining the inner face of the bush and provided with an opening to receive a cork, and means on said bush and integral therewith positioned adjacent said inner face to engage a side of the cork to obstruct only outward movement of the cork while offering substantially no resistance to inward movement of the cork and being so positioned as to offer no obstruction to the passage of a pump rod through the opening. 50
